(57) **CLAIM**

The ornamental design for a money clip, as substantially shown and described.

DESCRIPTION

FIG. 1 is a perspective view of the money clip;
FIG. 2 is a front plan view thereof;
FIG. 3 is a back plan view thereof;
FIG. 4 is a right side elevation view thereof;
FIG. 5 is a left side elevation view thereof;
FIG. 6 is a bottom elevation view thereof;
FIG. 7 is a top elevation side view thereof;
FIG. 8 is a perspective view of the money clip retaining currency shown in broken lines; and,
FIG. 9 is a perspective view of the money clip illustrating currency being inserted into the money clip by a user with the currency and user shown in broken lines.
The broken lines illustrating the currency and the fingertips of a user in FIGS. 8 and 9 are for illustrative purposes only and form no part of the claimed design.
